HEAT EXCHANGER FOR FLUIDS

Harvey Feldmeier, Little Falls, N. Y., assignor to
Cherry-Burrell Corporation, Wilmington, Del.,
a corporation of Delaware

Application November 4, 1933, Serial No. 696,658

10 Claims. (Cl. 257—183)

This invention relates to improvements in heat exchangers for fluids or liquid heaters and coolers of the surface type, in which a liquid, for example, milk, is caused to flow in thin films or layers over the outer surfaces of tubes or hollow heat exchange elements, to be cooled or heated by a cooling or heating medium circulating within the tubes or hollow elements. While this invention is particularly applicable to milk coolers and heaters, it is not limited to such use, but applies also to heat exchangers for other liquids. Well known surface milk heaters or coolers comprise a series of horizontal tubes arranged one above another or in a vertical bank with connections for circulating a heat exchange medium, such as cold or hot water or brine therethrough, a liquid distributor or device arranged to discharge milk to be cooled or heated onto the uppermost tube of the bank so that the liquid will flow downwardly in thin films or layers over the outer surfaces of the tubes in succession into a trough or receiver at the bottom of the bank of tubes, the milk in its passage over the tubes being cooled or heated by means of the heat exchange medium circulating through the tubes.

It is desirable in such devices to prevent the liquid being treated from spreading or flowing lengthwise on the tubes to their extreme ends or onto the headers, return bends or circulating connections for the heat exchange medium, in order to avoid waste of the liquid by dripping on or outwardly beyond the ends of the bottom receiver, and also to prevent contamination of the liquid by contact with possible condensation or leaking heat exchange medium on or from the headers or circulating connections. For this purpose, surface heat exchangers of this type have been provided with curbs or parts adjacent the ends of the tubes or spaced inwardly from the headers or circulating connections for limiting the flow of the liquid lengthwise on the tubes and preventing the liquid from reaching the headers or connections or spreading on the tubes out to the vertical planes of the ends of the bottom receiver. Such curbs are ordinarily formed by projecting collars, rings or flanges surrounding the tubes or vertical strips extending across and projecting outwardly from the surfaces of the tubes, which collars or strips are soldered, brazed or welded to the tubes. These previous constructions are objectionable in various respects. In the past, when it was the practice to make the heat exchanger tubes or elements of tinned copper, the curbs could be conveniently soldered on the tubes or elements, but the stainless steel and other stainless alloys now

demanded by the trade and commonly employed in the manufacture of surface heat exchangers are difficult to solder or braze and, furthermore, solder disintegrates in time and becomes porous and unsanitary. Therefore, when the heat exchangers are made from stainless steel or materials which do not solder or braze well, it has been essential to a high grade product to weld the curb rings or strips to the heat exchange tubes or elements. Welding or brazing operations are slower and more expensive than soldering, and if brazing or welding is used, considerable expense is entailed in grinding the corners to make smooth fillets to meet sanitary requirements, particularly in the case of milk heaters or coolers, thus materially increasing the cost of the devices.

One object of my invention is to provide a practical and desirable heat exchanger of the sort mentioned which avoids the above noted objections.

Other objects of the invention are to provide a surface heat exchanger for liquids having means of simple and inexpensive construction which will effectively limit the flow or spreading of the liquid lengthwise on the heat exchange surfaces so as to prevent the liquid from being wasted or reaching the headers or circulating connections for the heat exchange medium, and prevent contamination of the liquid by contact with condensation or leaking heat exchange medium; and also to provide a heat exchanger for liquids having the other features of improvement and advantage hereinafter described and set forth in the claims.

The accompanying drawings illustrate different practical embodiments of my invention. In said drawings:

Fig. 1 is a front elevation, partly in section, of a tubular liquid heater or cooler of one form embodying the invention.

Fig. 2 is a transverse section of the upper portion thereof, on an enlarged scale on line 2—2, Fig. 1.

Fig. 3 is a fragmentary front elevation on an enlarged scale, showing a slightly modified construction.

Fig. 4 is a fragmentary front elevation, partly in section, showing another modification of the invention.

In the embodiment of the invention illustrated in Fig. 1, the device comprises a number of substantially horizontal tubes 10 arranged in a vertical bank, or one above another, a liquid distributing trough or device 11 arranged above the tubes and adapted to discharge the liquid onto the top tube so that it will flow down in thin films over

the outer surfaces of the several tubes into the bottom trough or receiver 12 arranged below the tubes. The tubes may be provided with the usual longitudinal drip strips 10a along their bottoms, 5 and the first or top tube of each bank or section is preferably provided with a drip strip 10b along its top, as shown in Figs. 1 and 2. As shown, the tubes are arranged in two superposed sections or units, one above another, so that the liquid will 10 first flow over the tubes of one section to be cooled or heated by a medium flowing through these tubes and then flow over the tubes of the next section to be further cooled or heated by a colder or hotter medium, as the case may be, flowing 15 through the tubes of the lower section. But, insofar as this invention is concerned, the tubes can be arranged in a single section, or in a plurality of sections, and in a single or plurality of banks.

Any suitable means or connections may be provided 20 for circulating the cooling or heating medium through the tubes. As shown, the tubes 10 of each section are connected at their ends by suitable headers or return bends 13 to form a continuous coil or conduit so that a medium admitted, 25 for instance, to the bottom tube of the section through an end inlet pipe or connection 14, will flow in succession through the several tubes of this section and discharge through an outlet pipe or connection 15 at one end of the top tube of the 30 section. The headers may be constructed and connected with the ends of the tubes either permanently or removably, in any suitable manner. For instance, as shown in Fig. 1, the headers 13 are permanently attached to the tubes, but they 35 can be of any other suitable or known construction, such for example, as illustrated in Fig. 4, in which the tubes are secured at their ends in a common header 16 which is partitioned to provide chambers 17 communicating with corresponding 40 ends of adjacent tubes so as to connect the tubes one with another in series. The header has threaded openings in its outer wall which, as usual, are closed by removable screw plugs 18.

Each of the tubes 10 is straight and horizontal 45 for the major portion of its length, but is bent or made so as to form an upbent or upwardly extending portion 19 at each end of the tube which preferably slopes upwardly and outwardly at a slight angle of about ten degrees, to the horizontal portion 50 of the tube. The tubes being of substantially equal length, the upbent or sloping portions 19 at corresponding ends of the several tubes are disposed vertically one above another and so that the bends or angles between the horizontal and upbent 55 portions of the tubes are in vertical alignment one above another, and preferably in a vertical plane, which is disposed inwardly from the adjacent end wall of the bottom trough or receiver 12.

The liquid distributor 11 may be of any known 60 or suitable construction adapted to cause the liquid to flow downwardly in thin films over the outer surfaces of the tubes. The liquid films tend to spread out or flow lengthwise along the tubes but the films being thin, the upbent ends of the 65 tubes act as curbs to prevent the films from spreading or flowing substantially beyond the bends or angles connecting the upbent and horizontal portions of the tubes. Since the thin liquid films on the tubes will not creep or flow a substantial 70 distance up the inclines or slopes of the upbent end portions of the tubes, the films are effectively prevented from spreading lengthwise on the tubes outwardly beyond the ends of the bottom trough or receiver or into contact with the 75 headers joining the ends of the tubes. Thus, the

liquid is prevented from being wasted by dripping off the heat exchange surfaces outwardly beyond the ends of the bottom trough or receiver, and also from reaching the headers or return bends or joints between the same and the tubes.

The tubular section, or sections, in case more than one section is used, together with the liquid distributor and the bottom trough or receiver may be mounted in the stated relation in any suitable manner. As shown, the endwise projecting outlet pipe or connection 15 at one end of the top tube of each section and a corresponding endwise projecting part 20 provided at the opposite end of the section, bear on brackets 21 fixed on upright supporting posts 22 at the opposite ends of the 10 device. The bottom trough or receiver 12 is similarly supported by projections 23 at its ends resting on brackets 24 fixed on the lower portions of the posts 22. The distributor 11, as shown, is provided at its ends with legs 25 which are removably secured, as by thumb screws 26 to lugs formed on the top headers at the opposite ends of the upper section.

In the modified construction illustrated in Fig. 3, each of the tubes is bent or made to provide 25 adjacent each of its ends an upwardly offset portion 27 which is preferably of shallow inverted V-form having one leg 28 which slopes upwardly and outwardly from the horizontal portion of the tube, and an outer leg 29 which slopes downwardly toward the header, return bend or circulating connection at that end of the tube. These offset portions thus have parts sloping upwardly 30 in opposite directions to the crests or highest points of the offsets. The upwardly and outwardly sloping legs of the offsets act like the upbent ends 19 in the Fig. 1 construction, to prevent the creeping or flowing of the films outwardly or toward the ends of the tubes substantially beyond the angles between these sloping 35 parts and the horizontal portions of the tubes, and the inwardly and upwardly sloping legs prevent any liquid films which may be on the extreme ends of the tubes or the headers from flowing or creeping inwardly along the tubes. Thus, if there 40 should be any liquid on the extremities of the tubes, headers or circulating connections, due either to condensation or leakage of the heat exchange medium through faulty joints between the tubes and the headers, return bends or circulating 45 connections, such liquid would be prevented from creeping inwardly along the tubes into contact with the films of liquid being treated on the horizontal portions of the tubes. In other words, the upwardly offset portions prevent films of liquid 50 on the tubes at opposite sides of the crests of the offsets from creeping or flowing into contact with each other so as to permit contamination of the liquid being treated by mixture or contact with any heat exchange medium or condensation on 55 the end portions of the tubes, or the headers or circulating connections.

In each of the different embodiments of the invention illustrated, the upbent or offset portions of the tubes which curb or limit the endwise flow or creeping of the liquid on the tubes, are formed by integral portions of the tubes themselves, and no curbs or parts are used which have to be attached or secured to the tubes by soldering, welding or otherwise.

An additional advantage of the described tube construction is that some expansion and contraction, due to unequal temperatures, is possible without harm or objectionable distortion of the device, since the bent tubes are allowed a chance 75

to straighten or bend more without undue strain on the connected parts.

I claim as my invention:

1. A surface heat exchanger for fluids comprising a tube arranged substantially horizontally for a liquid film to flow over its outer surface transversely to the length of the tube for heat exchange with a medium within the tube, said tube having an upbent portion for limiting film flow lengthwise on the tube. 10

2. A surface heat exchanger for fluids comprising a tube arranged substantially horizontally for a liquid film to flow over its outer surface transversely to the length of the tube for heat exchange 15 with a medium within the tube, said tube having an upwardly offset portion for preventing contact of liquid films on the tube at opposite sides of the crest of said offset portion.

3. A surface heat exchanger for fluids comprising a tube arranged for a liquid film to flow over its outer surface transversely to the lengths of the tube for heat exchange with a medium within the tube, said tube having a horizontal portion and upwardly offset portions at opposite ends of 25 said horizontal portion.

4. A surface heat exchanger for fluids comprising a tube arranged for a liquid film to flow over its outer surface transversely to the length of the tube for heat exchange with a medium within the tube, said tube having a horizontal portion and a portion sloping upwardly from an end of 30 said horizontal portion.

5. A surface heat exchanger for fluids comprising a tube arranged substantially horizontally for a liquid film to flow over its outer surface transversely to the length of the tube for heat exchange with a medium within the tube, said tube having a shallow A shaped portion for limiting film flow lengthwise on the tube. 35

6. A heat exchanger for fluids comprising horizontal tubes arranged one above another, means

for causing a liquid to flow downwardly exteriorly over said tubes, and connections for circulating a heat exchange medium through said tubes, said tubes having portions thereof extending upwardly for limiting the flow of liquid lengthwise on the exteriors of the tubes. 5

7. A heat exchanger for fluids comprising horizontal tubes arranged one above another, means for causing a fluid to flow downwardly exteriorly over said tubes, and connections for circulating a heat exchange medium through said tubes, said tubes having upwardly sloping end portions for limiting the flow of liquid lengthwise on the exteriors of the tubes. 10

8. A heat exchanger for fluids comprising horizontal tubes arranged one above another, means for causing a fluid to flow downwardly exteriorly over said tubes, and connections for circulating a heat exchange medium through said tubes, said tubes having upwardly offset end portions for 20 preventing contact of liquid on the exteriors of the tubes at opposite sides of the crest of said offset portions. 15

9. A heat exchanger for fluids comprising tubes arranged one above another and having horizontal main portions and integral portions which extend upwardly from said main portions and are in substantial vertical alinement, means for causing a liquid to flow downwardly exteriorly over said horizontal main portions of the tubes, 30 and connections for circulating a heat exchange medium through the tubes. 25

10. A heat exchanger for fluids comprising a pair of headers with fluid passages therein, and horizontal tubes having upbent ends secured to the headers in communication with said passages, whereby liquid films flowing over the outside surfaces of the tubes are confined to the horizontal parts of the tubes. 35

HARVEY FELDMAYER.
